UNITED STATES PATENT OFFICE.

WILLIAM ROSEVEAR, OF McDONALD, OHIO.

LUBRICATING DEVICE.

Application filed April 3, 1925. Serial No. 20,420.

This invention relates to a lubricating device for rolling mill rolls and the like, and has for one of its objects the provision of means for causing a constant supply of 5 lubricant under pressure to the surface to be lubricated.

Another object is to provide a device of this class which will hold or force grease against the surface to be lubricated under 10 a constant pressure.

A further object is to provide a lubricating device having the novel construction, design and combination of parts described in detail in the following specification, and 15 illustrated in the accompanying drawings.

In the drawings:

Figure 1 is an end elevation of a stand of rolls having my invention applied thereto.

Figure 2 is a plan of the lubricating device.

Figure 3 is a sectional elevation taken on the line III—III of Figure 2.

Referring more particularly to the drawings, the numeral 2 designates a roll stand 25 housing of well known and standard design having the usual opening or window 3 in which are mounted the bearing blocks 4 for supporting the necks 5 of the rolling mill rolls.

The present invention is adapted to be mounted in the window 3 of the housing and comprises a grease retaining box 6 adapted to be supported as shown on the 35 lower bearing block 4 for each of the rolls.

The box 6 is composed of a bottom wall 7, end walls 8 and rear wall 9 are rigidly connected together. The end walls 8 have their forward free edges cut away as at 40 10 in a curve corresponding to the curvature of the roll necks 5 so as to snugly fit against said necks. The thickness of the box from front to back is such that it will have a relatively close fit between the side 45 wall of window 3 and roll neck 5.

The box 6 is adapted to be filled with heavy grease or other suitable lubricant A for greasing or lubricating the roll necks. In order to feed or force the grease or 50 other lubricant up against the roll neck, I provide a concavely curved grease compressing and feeding plate 12 which has its lower edge hingedly secured to the bottom wall 7 of the box 6 adjacent its forward free edge by hinge members 14. The curvature of the plate 12 corresponds to

the curvature of the surface or periphery of the roll neck so as to feed the grease evenly over the roll neck and also so as to permit all the grease to be used. 60

The plate 12 is adapted to be moved to its rearmost position and the grease or other lubricant filled in the box on top of the plate.

In order to facilitate the filling of the 65 box 6 with lubricant, one end wall is provided with a projecting filling spout 15.

A cam shaft 16 is journaled in the box 6 to the rear of the plate 12 and carries cams 17 adapted to engage against the rear face 70 of the plate 12.

The shaft 16 projects through the end walls 8 of the box 6 and a counterweight lever 18 is mounted on one end of the shaft and projects rearwardly along one side of 75 the roll housing 2 and is provided with a series of openings 19 for the reception of counterweight 20.

The force of the counterweight on the lever 18 tends to rotate the shaft 16 and 80 therefore provides a constant pressure of the cams 17 against the plate 12. This constant pressure against the plate 12 serves to force the lubricant under a constant pressure against the roll necks 5 thus automatically lubricating the roll necks. 85

The use of the lubricating device of this invention for lubricating the necks of rolling mill rolls tends to materially reduce friction on the mill, thus decreasing the 90 amount of power required, and also effecting a saving in rolls and roll bearings due to decrease in wear. Also, due to the close contact between the lubricant and roll neck, because of the constant pressure feed of the 95 lubricant the amount of water which gets between the lubricant and roll neck is greatly reduced thereby providing materially better lubrication of the roll necks.

While I have shown and described only 100 one specific embodiment of my invention, it will be understood that I do not wish to be limited thereto, since various modifications may be made without departing from the scope of my invention as defined in the 105 appended claims.

I claim:

1. An automatic greasing element for the 110 necks of rolling mill rolls, comprising a lubricant receiving box adapted to be mounted in fixed relation to the roll neck and to contain a quantity of grease, a curved grease

compressing and feeding plate hingedly secured along its lower edge to said box, said plate having substantially the same curvature as the periphery of the roll neck, and a 5 counterweighted means for forcing said plate and the grease toward the roll neck, so as to force said grease under pressure against said roll neck.

2. An automatic greasing element for the 10 necks of rolling mill rolls, comprising a lubricant receiving box adapted to be mounted in fixed relation to the roll neck and to contain a quantity of grease, a curved grease compressing and feeding plate hingedly se-

15 cured along its lower edge to said box, said plate having substantially the same curvature as the periphery of the roll neck, and means for forcing said plate and the grease toward the roll neck, so as to force said 20 grease under pressure against said roll neck.

3. The combination with a roll housing and roll of a rolling mill, of a grease box 25 mounted in the window of the roll housing for greasing the neck of the rolls, said box being composed of a rear side, end and bottom walls and being positioned with its open side toward the roll neck, said box being adapted to contain a quantity of grease, a curved grease compressing and feeding plate 30 mounted in, and hingedly secured along its lower edge to said box, and means for forcing said plate and the grease toward the roll neck so as to force said grease under pressure against said roll neck.

4. The combination with a roll housing 35 and roll of a rolling mill, of a grease box mounted in the window of the roll housing for greasing the neck of the roll, said box being composed of a rear side, end and bottom walls and being positioned with its open 40 side toward the roll neck, said box being adapted to contain a quantity of grease, a curved grease compressing and feeding plate having its lower edge hingedly connected to the bottom wall of said box along its open 45 side, and a counterweighted means for forcing said plate and the grease toward the roll neck.

5. The combination with a roll housing and roll of a rolling mill, of a grease box 50 mounted in the window of the roll housing for greasing the neck of the roll, said box being composed of a rear side, end and bottom walls and being positioned with its open side toward the roll neck, said box being 55 adapted to contain a quantity of grease, a curved grease compressing and feeding plate having its lower edge hingedly connected to the bottom wall of said box along its open side, a shaft journaled in said box, a cam on said shaft, and means for operating said shaft to force said cam against said plate so as to move said plate forwardly toward the roll neck and thereby force the grease 60 into contact with the roll neck. 65

In testimony whereof, I have hereunto set my hand.

WILLIAM ROSEVEAR.
